CLAIM

The ornamental design for a cyclometer for e-bikes, as shown and described.

DESCRIPTION

FIG. 1 is a perspective view of the cyclometer for e-bikes;

FIG. 2 is a front view thereof;

FIG. 3 is a rear view thereof;

FIG. 4 is a top view thereof;

FIG. 5 is a bottom view thereof;

FIG. 6 is a side view thereof;

FIG. 7 is an opposite side view thereof; and,

FIG. 8 is another perspective view thereof.

The broken lines in the drawings illustrate portions of the cyclometer for e-bikes that form no part of the claimed design.
